UNITED STATES PATENT OFFICE.

HENRY F. WORNER, OF PHILADELPHIA, PENNSYLVANIA.

RADIORECEIVER.

Application filed August 21, 1924. Serial No. 733,315.

My invention relates to new and useful improvements in a radio receiver, and has for one of its objects to simplify the construction of such devices whereby the tuning may be accomplished through the medium of a single control preferably in the form of a lever or crank.

Another object of this invention is to provide for coupling two variable condensers together whereby they will be actuated in unison from a single control.

A further object of this invention is to provide an indicator associated with the tuning elements in such manner that the wave length setting of the tuning elements will be shown on the indicator.

A still further object of the invention is to provide a pilot light so connected in the filament circuit of the vacuum tube or valve that said pilot light will be lit only when the above mentioned filament circuit is turned on.

Still another object of this invention is to provide pointers in connection with the control means operating in conjunction with a dial on which different stations may be marked to indicate the different settings of the tuning element whereby the wave lengths of different stations may be tuned to without the necessity of referring to the indicator after a station has been once tuned in.

With these ends in view, this invention consists in the details of construction and combination of elements hereinafter set forth and then specifically designated by the claim.

In order that those skilled in the art to which this invention appertains, may understand how to make and use the same, I will describe its construction in detail, referring by numerals to the accompanying drawings forming a part of this application, in which:

Fig. 1 is a front elevation of a radio receiver embodying the invention.

Fig. 2 is a rear elevation thereof.

Fig. 3 is a side elevation of the same.

Fig. 4 is an opposite side view thereof.

Fig. 5 is a diagram of the circuits utilized in the receiver herein illustrated.

Fig. 6 is a front elevation or front end view of the tuning elements per se showing the manner of coupling the two variable condensers and the relation thereof to the control or operating means.

In carrying out the invention as here em-

bodied, 10 represents a panel of suitable material and which supports the tuning elements preferably through the medium of a sub-panel 11 and therefore will be thus described, although it will be obvious that the device or the several parts thereof may be supported in any well known or desirable manner. As herein illustrated the sub-panel 11 is attached to the main panel 10 by any suitable well known fastening devices 12, such as screws and the necessary coacting nuts. Associated with the sub-panel 11 are two variable condensers 13 and 14 both of which are associated with the inductance coil 15 certain details of which will be hereinafter more fully explained while the constructional data is set forth in detail in my application for patent, bearing Serial Number 689,582, dated January 30th, 1924. Both 75 of the variable condensers include the ordinary elements of devices of this character such as the stator or stationary plates 16, the rotor or movable plates 17 each mounted on a shaft 18. The shaft of the condenser 14 has a control means or operating element 19 connected therewith which control is preferably in the form of a double handle crank or lever, as plainly shown in Fig. 6, while intermediate the ends of said double lever 80 controller are a pair of pointers 20-21 projecting in opposite directions and adapted for movement across the face of the dial 22 in an arcuate path, said dial being fixed to the outer surface of the panel 10. At the 85 outer ends of the lever arms are fixed grips 23 or knobs whereby an operator may actuate the control from either end of the lever while at the center of said control lever is located a suitable knob 24 by which said control lever may be actuated if desired. This control lever is preferably connected with the shaft 18 of the condenser 14 by means of the socket 26 telescoping over the end of the condenser shaft and being held in proper adjustment by a screw 27.

Because of the unique construction or arrangement of the coil or inductances it has been found that if the rotors of the two condensers are in practically identical positions 105 when tuning in a broadcast wave the loudest signals are usually obtained but due to conditions in the course of manufacture of variable condensers the capacities may and do vary to some extent therefore the two 110 condensers to be used in any set are generally calibrated so that when the receiver is actu-

ally in use the rotor of one condenser may have a considerably different setting from the rotor of the other condenser although their capacity will be substantially the same.

- 5 The rotors of the two condensers are coupled together by means of two clamp arms 28 and 29 adjustably fastened to the rotor shafts of the condensers 13 and 14 respectively, by means of screws 30 or their equivalent, and a connector or link 31 having its ends pivotally connected with the outer ends of the clamp arms 28 and 29, as shown in Fig. 6, and said clamp arms 28 and 29 are so located with respect to each other that 10 there is no dead center and therefore the two rotors will not become "locked."

From the foregoing description it will be seen that when the control means or operating lever 19 is actuated the rotors of the 20 two condensers will be rotated in unison in fixed relation to vary their capacities in the same ratio, in other words, the plates of the rotors of both condensers will be withdrawn from or projected between the plates of the 25 stators in unison as the control lever is rotated.

In order to visibly indicate the wave length of the settings of the variable condensers, or in other words, the setting of the 30 condensers at which they will receive broadcasts of certain wave lengths, I provide an indicator 32 comprising a dial and pointer one element of which is connected with the variable condensers and I do not wish to be 35 limited to the specific arrangement of the parts herein illustrated as these are shown only as an illustration of the embodiment of my invention. As here shown the indicator includes a dial 33 adjustably connected 40 with the shaft of the condenser 13 by means of a screw 34 or its equivalent, and this dial has wave length markings thereon visible through the sight opening 35 in the front panel 10 and as here shown these markings 45 represent meters. This dial is rotatable across the sight opening 35 and the pointer 36 is shown as a hair line which may be produced on transparent material disposed across the sight opening or it may be merely 50 a thread, wire or the like stretched across said sight opening.

The indicator being adjusted to the calibration of the condensers and moving in unison therewith for the wave length of a 55 broadcasting station as known it is only necessary to turn the control lever until said indicator shows such wave length and if at that time such broadcasting station is on the air the broadcast program will be received 60 on the radio receiver. Because of the usual restricted area of the indicator dial the markings must be restricted to about every ten meters so that for a station on 509 meters, for instance, it will be necessary to move the tuning element until 510 meters is

shown on the indicator and then by slowly moving the tuning element slightly until the broadcast program is received at its maximum. After this has been done the station may be logged on the logging dial 22 by 70 drawing a line on said dial opposite the position of one of the pointers 20 of the tuning lever and marking the same with the call letters of the station or the wave length and where two stations use the same wave length 75 one station may be placed on the dial at one side of the horizontal diameter of the logging dial while the other station is marked on the other side horizontal diameter since the tuning element operates only a one-half 80 revolution and therefore one of the pointers as 20 will coat with the markings on one-half of the logging dial while the other pointer 21 will cooperate with the markings 85 on the other half of said logging dial.

The inductance coil 15 includes three inductances 37, 38 and 39, Fig. 5, and the inductance 37 is connected by conductors 40 and 41 with the variable condenser 13 so that said inductance is in series with the condenser and form a closed oscillatory circuit sometimes called an absorption or "losser" circuit.

The primary inductance 38 is connected by a conductor 42 with the aerial binding post 43 to which the lead-in wire from the antenna is connected in the usual manner and said inductance is also connected by a conductor 44 with the ground binding post 45, the latter having the ground wire connected therewith in the usual manner.

The ground binding post is connected by a conductor 46 with the binding post 47 which is for connection with the minus terminal of the A battery and in turn this binding post 47 is connected by a conductor 48 to a suitable rheostat 49 while the other side of the rheostat is connected by a conductor 50 with a contact 51 of the jack 52 and another contact 53 is connected by a conductor 54 with one side of the filament of the vacuum tube or valve socket 55, the vacuum tube being represented by the numeral 56 in the diagram while the other side of the filament is connected by a conductor 57 leading from the tube socket to the plus A battery binding post 58, said binding post also adapted for connection with the minus terminal of the B battery.

The binding post 59 to which the plus terminal of the B battery is connected has one end of a conductor 60 connected thereto which conductor leads to the contact 61 of the jack.

One side of the secondary inductance 39 is connected by a conductor 62 with the fixed condenser 63 which in turn is connected with the grid terminal of the vacuum tube by a conductor 64 while the other side of the secondary inductance is connected by a con-

ductor 65 with the plate terminal of the vacuum tube socket and across these connections is shunted the other variable condenser 14, preferably by means of conductors 66 and 67.

The plate circuit is connected by a conductor 68 with the contact 69 of the jack.

In the front panel 10 is located a socket 70 of a pilot lamp designated in the diagrammatic view by the numeral 71 and one side of this pilot lamp socket is connected by a conductor 72 with the binding post 58 which as before stated is adapted for connection with the plus terminal of the A battery while the other side of the pilot lamp socket is connected by a conductor 73 with the variable resistance 74 which in turn is connected by a conductor 75 with the contact 53 of the jack so as to be in the circuit 20 leading to the minus terminal of the A battery.

The use of the variable resistance in the pilot lamp circuit is shown only to illustrate the manner in which the voltage may be reduced for use with a relatively small pilot light so as to prevent or reduce the possibility of injury to said lamp and likewise reduce the current consumption thereof.

From this it will be seen that when the 30 rheostat is actuated to turn on the filament current to the vacuum tubes, the pilot light being in shunt therewith will be lit when the filament current is turned on and will thus indicate to the operator that the 35 filaments of the vacuum tubes are functioning properly.

Although I have described only a detector circuit it will be obvious that the pilot light may be connected with the amplifying vacuum tubes so that unless all of said

tubes are burning the pilot lamp will not light. This is essential as the vacuum tubes are enclosed with a cabinet behind the solid front panel and cannot be seen by the operator. Such an arrangement also eliminates the necessity of connecting apertures either in the cabinet or panel. 45

From the foregoing description it will be noted that I have provided a radio receiver wherein the operator has but a single control for tuning said receiver to a broadcast wave and the desired wave may be immediately tuned to by reference to the wave length dial or the logging dial and through the medium of the pilot light the operator 50 knows whether or not the vacuum tubes are lit without having to peer through peepholes or opening the cabinet. 55

Of course I do not wish to be limited to the exact details of construction as herein 60 shown as these may be varied within the limits of the appended claim without departing from the spirit of my invention.

Having thus fully described my invention, what I claim as new and useful is:— 65

A radio receiver including a pair of variable condensers having rotors carried by shafts, clamp arms loosely mounted on the shafts of the rotors, means pivotally connecting the free ends of the clamp arms a 70 predetermined distance apart, means securing the shaft engaging ends of the clamp arms to the shafts whereby the rotors can be freed for adjustment independently of the clamp arms and one another, and operating means connected to the shaft of one rotor. 75

In testimony whereof, I have hereunto affixed my signature.

HENRY F. WORNER.
